UNITED STATES PATENT OFFICE

2,505,714

FIRE EXTINGUISHER

Claude Adelard Martel, Montreal, Quebec,
Canada

Application August 11, 1948, Serial No. 43,683

11 Claims. (Cl. 169—29)

1

The present invention pertains to a novel fire extinguisher to be mounted in or on a ceiling.

The principal object of the invention is to provide a device of this character containing a supply of fire-extinguishing liquid under pressure and adapted to discharge the same when a predetermined unsafe temperature is attained. Another object is to provide in the extinguisher a switch that is actuated to operate an alarm under the same conditions.

Still another object is to provide such a device that is set in operation by the separation of a fusible link and by the detonation of a cartridge on severing of the link.

In the accomplishment of these objects, the device includes a rod, preferably threaded, inserted in the ceiling and on which is mounted the container for the extinguishing fluid. The container has a double bottom and is perforated beneath the upper bottom. The upper bottom has a discharge opening normally covered by a frictionally held cap.

A cartridge is carried by the container and is fired by a detonating pin released by the severing of a fusible link. The gas under pressure released by the cartridge removes the aforementioned cap to permit the fluid to flow to the apertures beneath the upper bottom.

Other objects and advantages will appear as the description proceeds.

The invention is fully disclosed by way of example in the following description and in the accompanying drawings in which:

Figure 1 is a vertical section of the device;

Figure 2 is a section on the line 2—2 of Figure 1;

Figure 3 is a perspective view of a detail;

Figure 4 is a detail section at a right angle to Figure 1;

Figure 5 is a complete section at a right angle to Figure 1, showing a different position of parts;

Figure 6 is a perspective view of the valve cap;

Figures 7, 8 and 9 are elevations of modified guide screws;

Figure 10 is an elevation of a modified construction;

Figure 11 is a detail vertical section at a right angle to Figure 1;

Figure 12 is a similar section showing the lowered position of the container;

Figure 13 is an enlarged detail of Figure 12; and

Figure 14 is a plan section at a lower lever than Figure 2.

Reference to these views will now be made

2

by use of like characters which are employed to designate corresponding parts throughout.

In Figure 1 is shown a ceiling 1 in which is concealed a housing 2 that is open at the surface of the ceiling. In the housing is slidably mounted a container 3 having a central sleeve or core 4 passing through the bottom 5. The container includes a dish 6 fastened to the wall of the container and engaging the lower end of the core 4, thereby forming a double bottom. The dish has angular holes 7 normally closed against the housing 2, as shown in Figure 1.

Axially in the core 4 is positioned a rod 8 having a helical groove 9 and threaded at 10 at its upper end for fastening in the ceiling. Directly over the container 3 the rod 8 is formed with a plate 11 and above this with a lug 12 carrying a switch box 13. The switch is operated by a lever 14 terminating in a ball 15. A leaf spring 16 is passed beneath and over the switch box and carries a socket member 17 that receives the ball 15. The end of the lower lap of the spring carries a hammer 18 through which is passed a pin 19 exposed at the lower end and carrying a hook 20 at the upper end. The spaced end of the upper lap carries a hook 21, and the hooks are joined by a two-part fusible link 22, shown in Figures 4 and 5.

In the upper end of the core 4 is fastened a disk 23 carrying a single ball 24 adapted to ride in the groove 9. Thus, the container 3 may rotate and descend on the rod 8 under its weight when free. The lower end of the rod carries a similar disk 25 (Fig. 13) carrying lateral ball bearings 26 engaging the core and surface bearings 27 to be engaged by the descended disk 23. In this position the ball 24 lodges in a circular groove 28 at the lower end of the rod 8 and rests on a shoulder 29 at the lower extremity.

A small off-center tube 30 passes through the top and bottom of the container 3. In the upper end of the tube is a shoulder 31 on which hangs an explosive cartridge 32. Over the cartridge is a screw plug 33 through which is passed a slideable pin 34 adapted to strike the detonator of the cartridge. The upper end of the pin has an exposed head 35 lying beneath the pin 19. A strip 36 is fastened to the plate 11 and has an aperture 37 which receives the head 35. The container 3 is thus held from rotating and descending.

Adjacent to the tube 30, the bottom 5 of the container is formed with an opening 38 rimmed by a depending flange 39. A cap 40 has a circular groove 41 and a smaller recess 42 adapted

to fit frictionally on the flange 39 and the exposed end 43 of the tube 30, respectively.

The container 3 is nearly filled with a fire-extinguishing liquid, such as carbon tetrachloride under gas pressure charged through a valve 44 in the top of the container, as shown in Figure 12. The valve is preferably of the sliding pin type and is held closed by a spring 45. The pressure of the gas or air is determined by the size of the room in which is placed the invention.

Modified forms of guide screws consisting of twisted stock are shown in Figures 7, 8 and 9 and designated by the numerals 46, 47 and 48 respectively.

In the modification shown in Figure 10, the device is exposed beneath the ceiling. A cap 50 is held against the ceiling by a screw 8' which carries a switch block 13', plate 11' and associated parts as in Figure 4. A container 3' rides on the rod 8' as previously set forth.

In the operation of the first embodiment, the fusing temperature separates the link 22 as in Figure 2. Such links may be provided at 25° intervals of fusing temperature in a range from 125° to 500° F. On separation of the link 22, the pin 19 strikes the head 35 of the pin 34 to detonate the cartridge 32. The head 35 is also driven out of the opening 37, freeing the container 3 to rotate and descend under its weight. The strip 36 is formed with a hump 49 to keep the pin 19 from remaining in the hole 37 and preventing the container from rotating.

The gas released under pressure from the cartridge blows the cap 40 off the bottom 5. The contents of the container fill the dish 6 and are sprayed in all directions from the apertures 7 as the latter clear the housing 2.

The expansion of the spring 16 actuates the switch lever 14 and operates an alarm (not shown) connected to the switch by wires 51.

The modification shown in Figure 10 operates in like manner.

Although specific embodiments of the invention have been illustrated and described, it will be understood that various alterations in the details of construction may be made without departing from the scope of the invention as indicated by the appended claims.

What I claim as my invention is:

1. A fire extinguisher comprising a rod adapted to be suspended from a ceiling, a fluid container adapted to ride on said rod and having a double bottom, the wall of said container being apertured beneath the upper bottom, a tube passing through the top and the upper bottom of said container, a cartridge in the upper end of said tube, a temperature-operated pin positioned to strike and detonate said cartridge, said upper bottom having a discharge opening, a housing normally covering the apertured portion of said container wall, said portion being movable beyond said housing as the container rides on said rod, means locking said container in said housing and disposed in the path of said pin to be released on movement of the pin and a cap frictionally and removably held against said opening and the lower end of said tube, whereby to be removed on explosion of said cartridge and form a fluid path through said upper bottom to the apertured wall portion of said container as the latter rides on said rod and beyond said housing.

2. A fire extinguisher comprising a rod adapted to be suspended from a ceiling, a fluid container adapted to ride on said rod and having a double bottom, the wall of said container being aper-

tured beneath the upper bottom, a tube passing through the top and the upper bottom of said container, a cartridge in the upper end of said tube, a bowed spring supported by said rod, a fusible link joining the ends of said spring, a pin carried by said spring and positioned to strike and detonate said cartridge on expansion of the spring, a housing normally covering the apertured portion of said container wall, said portion being movable beyond said housing as the container rides on said rod, means locking said container in said housing and disposed in the path of said pin to be released on movement of the pin said upper bottom having a discharge opening, and a cap frictionally and removably held against said opening and the lower end of said tube, whereby to be removed on explosion of said cartridge and form a fluid path through said upper bottom to the apertured wall portion of said container as the latter rides on said rod and beyond said housing.

3. A fire extinguisher comprising a rod adapted to be suspended from a ceiling, a fluid container adapted to ride on said rod and having a double bottom, the wall of said container being apertured beneath the upper bottom, a tube passing through the top and the upper bottom of said container, a cartridge in the upper end of said tube, a bowed spring supported by said rod, a fusible link joining the ends of said spring, a pin carried by said spring and positioned to strike and detonate said cartridge on expansion of the spring, a housing normally covering the apertured portion of said container wall, said portion being movable beyond said housing as the container rides on said rod, means locking said container in said housing and disposed in the path of said pin to be released on movement of the pin, said upper bottom having a discharge opening, a switch mounted adjacent to said rod and adapted to be actuated by said spring on expansion thereof to operate an external circuit, and a cap frictionally and removably held against said opening and the lower end of said tube, whereby to be removed on explosion of said cartridge and form a fluid path through said upper bottom to the apertured wall portion of said container as the latter rides on said rod and beyond said housing.

4. A fire extinguisher comprising a threaded rod adapted to be suspended from a ceiling, a fluid container enclosing said rod and having a double bottom, means on said container adapted to ride in the thread of said rod, the wall of said container being apertured beneath the upper bottom, a tube passing through the top and the upper bottom of said container, a cartridge in the upper end of said tube, a temperature-operated pin positioned to strike and detonate said cartridge, a housing normally covering the apertured portion of said container wall, said portion being movable beyond said housing as the container rides on said rod, means locking said container in said housing and disposed in the path of said pin to be released on movement of the pin, said upper bottom having a discharge opening, and a cap frictionally and removably held against said opening and the lower end of said tube, whereby to be removed on explosion of said cartridge and form a fluid path through said upper bottom to the apertured wall portion of said container as the latter rides on said rod and beyond said housing.

5. A fire extinguisher comprising a threaded rod adapted to be suspended from a ceiling, a

fluid container enclosing said rod and having a double bottom, means on said container adapted to ride in the thread of said rod, the wall of said container being apertured beneath the upper bottom, a tube passing through the top and the upper bottom of said container, a cartridge in the upper end of said tube, a bowed spring supported by said rod, a fusible link joining the ends of said spring, a pin carried by said spring and positioned to strike and detonate said cartridge on expansion of the spring, a housing normally covering the apertured portion of said container wall, said portion being movable beyond said housing as the container rides on said rod, means locking said container in said housing and disposed in the path of said pin to be released on movement of the pin, said upper bottom having a discharge opening, and a cap frictionally and removably held against said opening and the lower end of said tube, whereby to be removed on explosion of said cartridge and form a fluid path through said upper bottom to the apertured wall portion of said container as the latter rides on said rod and beyond said housing.

6. A fire extinguisher comprising a threaded rod adapted to be suspended from a ceiling, a fluid container enclosing said rod and having a double bottom, means on said container adapted to ride in the thread of said rod, the wall of said container being apertured beneath the upper bottom, a tube passing through the top and the upper bottom of said container, a cartridge in the upper end of said tube, a bowed spring supported by said rod, a fusible link joining the ends of said spring, a pin carried by said spring and positioned to strike and detonate said cartridge on expansion of the spring, a housing normally covering the apertured portion of said container wall, said portion being movable beyond said housing as the container rides on said rod, means locking said container in said housing and disposed in the path of said pin to be released on movement of the pin, said upper bottom having a discharge opening, a switch mounted adjacent to said rod and adapted to be actuated by said spring on expansion thereof, to operate an external circuit, and a cap frictionally and removably held against said opening and the lower end of said tube, whereby to be removed on explosion of said cartridge and form a fluid path through said upper bottom to the apertured wall portion of said container as the latter rides on said rod and beyond said housing.

7. A fire extinguisher comprising a threaded rod adapted to be suspended from a ceiling, a fluid container enclosing said rod and having a double bottom, means on said container adapted to ride in the thread of said rod, the wall of said container being apertured beneath the upper bottom, a tube passing through the top and the upper bottom of said container, a cartridge in the upper end of said tube, a temperature operated pin positioned to strike and detonate said cartridge, a housing normally covering the apertured portion of said container wall, said portion being movable beyond said housing as the container rides on said rod, means locking said container in said housing and disposed in the path of said pin to be released on movement of the pin, said upper bottom having a discharge opening, a striking pin in said tube and engageable by said detonating pin, a strip fastened to said rod and having an aperture slidably receiving said striking pin, and a cap frictionally and removably held against said opening and the

lower end of said tube, whereby to be removed on explosion of said cartridge and form a fluid path through said upper bottom to the apertured wall portion of said container as the latter rides on said rod and beyond said housing.

8. A fire extinguisher comprising a threaded rod adapted to be suspended from a ceiling, a fluid container enclosing said rod and having a double bottom, means on said container adapted to ride in the thread of said rod, the wall of said container being apertured beneath the upper bottom, a tube passing through the top and the upper bottom of said container, a cartridge in the upper end of said tube, a bowed spring supported by said rod, a fusible link joining the ends of said spring, a pin carried by said spring and positioned to strike and detonate said cartridge on expansion of the spring, a housing normally covering the apertured portion of said container wall, said portion being movable beyond said housing as the container rides on said rod, means locking said container in said housing and disposed in the path of said pin to be released on movement of the pin, said upper bottom having a discharge opening, a striking pin in said tube and engageable by said detonating pin, a strip fastened to said rod and having an aperture slidably receiving said striking pin, and a cap frictionally and removably held against said opening and the lower end of said tube, whereby to be removed on explosion of said cartridge and form a fluid path through said upper bottom to the apertured wall portion of said container as the latter rides on said rod and beyond said housing.

9. A fire extinguisher comprising a threaded rod adapted to be suspended from a ceiling, a fluid container enclosing said rod and having a double bottom, means on said container adapted to ride in the thread of said rod, the wall of said container being apertured beneath the upper bottom, a tube passing through the top and the upper bottom of said container, whereby said tube is adapted to communicate with the lower portion of said container, a cartridge in the upper end of said tube, a bowed spring supported by said rod, a fusible link joining the ends of said spring, a detonating pin carried by said spring, a housing normally covering the apertured portion of said container wall, said portion being movable beyond said housing as the container rides on said rod, means locking said container in said housing and disposed in the path of said pin to be released on movement of the pin, said upper bottom having a discharge opening, a striking pin in said tube and engageable by said detonating pin, a strip fastened to said rod and having an aperture slidably receiving said striking pin, a hump on said strip and engageable by said spring to hold said detonating pin out of said aperture, and a cap frictionally and removably held against said opening and the lower end of said tube, whereby to be removed on explosion of said cartridge and form a fluid path through said upper bottom to the apertured wall portion of said container as the latter rides on said rod and beyond said housing.

10. A fire extinguisher comprising a rod adapted to be suspended from a ceiling, a fluid container adapted to ride on said rod and having a double bottom, the wall of said container being apertured beneath the upper bottom, a tube passing through the top and the upper bottom of said container, a cartridge in the upper end of said tube, a temperature-operated pin positioned to strike and detonate said cartridge, a housing

normally covering the apertured portion of said container wall, said portion being movable beyond said housing as the container rides on said rod, means locking said container in said housing and disposed in the path of said pin to be released on movement of the pin, said upper bottom having a discharge opening, and a cap frictionally and removably held against said opening and the lower end of said tube, whereby to be removed on explosion of said cartridge and form a fluid path through said upper bottom to the apertured wall portion of said container as the latter rides on said rod and beyond said housing.

11. A fire extinguisher comprising a rod to be suspended from a ceiling, a fluid container adapted to ride on said rod, said container having a double bottom, the wall of said container being apertured beneath the upper bottom, a tube passing through the top and the upper bottom of said container, a cartridge in the upper end of said tube, a temperature-operated pin positioned to strike and detonate said cartridge, a housing normally covering the apertured portion

of said container wall, said portion being movable beyond said housing as the container rides on said rod, means locking said container in said housing and disposed in the path of said pin to be released on movement of the pin, said upper bottom having a discharge opening, and a cap frictionally and removably held against said opening and the lower end of said tube, whereby to be removed on explosion of said cartridge and form a fluid path through said upper bottom to the apertured wall portion of said container as the latter rides on said rod and beyond said housing.
